REGENERATIVE CHAMBER OVEN FOR THE
PRODUCTION OF COKE AND GAS

Hermann Petsch, Recklinghausen, Germany, assignor to Carl Still Gesellschaft mit beschränkter Haftung, Recklinghausen, Germany, a corporation of Germany

Application March 16, 1931, Serial No. 523,090
In Germany March 22, 1930

1 Claim. (Cl. 202—135)

The invention consists in improvements and special constructions of regenerative chamber ovens for the production of coke and gas, more particularly of the type in which a plurality of 5 regenerative chambers is arranged in parallel in each half of the substructure of the oven, extending in the form of tunnels over the whole length of the battery.

A characteristic feature of the invention consists in the provision in each half of the substructure of two pairs (four in all) of regenerator chambers arranged in parallel and supporting walls between or by the side of all the chambers. In a particular form of construction, the two 15 pairs of regenerative chambers adjoining the external sides of the oven battery are adapted for preheating gas for combustion or selectively either the gas or air for combustion, while the other pair of regenerator chambers arranged towards the middle of the oven are provided exclusively for preheating the air for combustion. This construction is adapted for working the oven with poor gas, that is gas of low calorific value, which usually requires preheating, or also 20 for working selectively with either poor gas or rich gas.

A further characteristic feature of the invention, which can be used when the chamber ovens are heated with preheated poor gas, consists in 30 a special arrangement of the passages for leading the combustion media, gas and air, preheated in the said regenerators, into the heating flues. An object of the latter arrangement is to improve the combustion and heating process in 35 the flues forming the heating walls.

An embodiment of the invention is represented by way of example in the accompanying drawings in which:

Figs. 1a and 1b, which are to be combined, 40 are vertical longitudinal sections; Fig. 1a is a section through an oven chamber on the line Ia—Ia of Figs. 2 and 3, and Fig. 1b is a section through a heating wall of a horizontal coke oven on the line Ib—Ib of Figs. 2 and 3.

Fig. 2 is a vertical cross-section on the line II—II of Fig. 1a, and Fig. 3 is a vertical cross-section on the line III—III of Fig. 1b.

Each of the two last-mentioned cross-sections include a part of the whole battery, comprising three heating walls or oven chambers.

The oven is adapted according to the usual construction for a reversal of the direction of flow of the products of combustion, so that at 55 any time one half of the heating walls is heated by the ascending gases for combustion, while the other half of the heating walls is traversed by the descending waste gases flowing to the regenerators. Within the heating walls are vertical heating flues H in which the products of

combustion are burnt from below upwards. Below each half of the heating walls there is a gas distributing passage a with nozzles b for rich gas which is connected by means of pipes f and cocks h with both gas mains g. Below the oven chambers K (Figs. 2 and 3) are alternately arranged pairs of sole flues c and d, each of which extends over one half of the oven. The flues c are connected by branch passages m and the flues d by branch passages n with vertical distributing ducts i or j provided in the partition walls s and t of the flues H, and are provided with lateral outlets e or o at different levels in the heating flues H.

In each substructure half of the oven, that is both in Fig. 1a and Fig. 1b, there are two pairs of parallel regenerator chambers R or L, that is altogether four chambers, which extend in the form of tunnels over the whole oven battery and are separated by walls M which act as pillars supporting the whole upper structure. The regenerator chambers R, as shown in Fig. 2, are divided by vertical partition walls k into as many separate chambers as there are heating walls, while the regenerator chambers L, as shown in Fig. 3, extend freely without such partitions over the whole length of the oven battery. Above each separate chamber of the regenerators R there is a horizontal inspection channel U provided (Figs. 1a and 1b) with a sight opening u in the front end of the oven. These regenerative chambers R communicate by small hollow shafts r with the flues c in the oven sole and the regenerators L communicate by similar shafts l with the flues d in the chamber sole. The crowns of all the regenerator chambers containing shafts r or l are, preferably, formed as shown in Figs. 1a and 1b by inclined projections V of the walls M separating the chambers, obviating the provision of the roof arches, with the drawback of 40 their lateral thrusts, which would otherwise be necessary. Passages w are provided below the regenerator chambers R and are connected by elbow pieces z with the waste gas collecting flues Q extending over the whole length of the 45 battery and leading to the chimney stack. Hinged covers x for opening into the atmosphere are provided at the elbow pieces z and closing flaps y are provided in the passage leading to the flues Q. Branch pipes q from the elbow pieces z form the connection by means of the cocks h with the gas mains g.

Below the regenerator chambers L are flues P which communicate with the regenerators by hollow shafts p and extend also over the whole 55 length of the battery and are provided at the end of the battery with a reversing valve (not shown), so that at any time the flues P of the one half of the oven, for example Fig. 1a, serve for drawing in the air for combustion, while, 60

at the same time, the flues P of the other half of the oven, Fig. 1b, lead away the waste gases to the chimney stack.

The sole flues c and d serve, when the corresponding half of the heating walls is heated by ascending burning gases, for the distribution over this half of the heating walls of the pre-heated gas or air for combustion withdrawn from the regenerators R and L to the individual heating flues H. The necessary connection of the flues c and d for this purpose with the heating flues H is, according to a feature of the invention, established by the vertical ducts i and j arranged in the partitions of the heating walls, which ducts are provided with a plurality of outlets e or o arranged at different levels and are connected below by the branch passages m and n with the flues c and d. The arrangement is such that at any time the ducts i of the even numbered partition walls s are connected with the flues c and the regenerators R, while, on the other hand, the ducts j of the alternate odd-numbered partition walls t are connected with the flues d and the regenerators L.

Also, in the described arrangement, according to the invention, there may be the further feature that the cross-sections of the outlets e of one group of ducts i are different from the cross-sections of the outlets o of the other group of ducts j. The object and the result of this particular arrangement are explained later.

The coke oven as described is adapted for the selective heating by either poor or rich gas. In heating with poor gas, the action is as follows:—

The gas mains g are supplied with poor gas. The pipes f, which are provided for rich gas, are shut off from the gas mains g, the branch pipes q have free connection up to the cocks h. The covers x on the elbow pieces z are permanently closed on both sides of the oven as shown in Figs. 1a and 1b. On the assumption, that the right half of the heating walls, corresponding to Fig. 1b, is to be heated by the gas and the left half of the heating walls carries away the waste combustion gases, the valves y are opened on the elbow pieces z on the left half side and closed on the right half side. The heating gas passes from the gas main g on the right (Fig. 1b), through the open cock h and the pipe q into the elbow piece z and from there through the passage w, forming a continuation of the elbow piece, into the pair of gas regenerators R on the right hand side, then through the hollow shaft r into the flues c on the right hand side, through the branch passage m into the vertical ducts i of the partition walls s and from these through the lateral openings e, which are distributed at different levels, into the heating flues H.

The air for combustion flows from the reversing valve (not shown) at the end of the battery into the flues P, shown in Fig. 1b, thence through the hollow shafts p into the regenerator chambers L and through the upper shafts l into the sole flues d, from them through the branch passages n into the vertical ducts j of the partition walls t and then through the lateral outlets o, also at different levels, into the flues H, in which the ignition of the air and gas occurs step by step at the various levels. The mass of burnt gases flows within the heating walls into the upper horizontal collecting flue v, from there is discharged into the flues H on the left half of the heating walls, and is withdrawn through the

ducts i and j on that side into the corresponding sole flues c and d which lead to the regenerators R and L (Fig. 1a). The waste gases from the one pair of regenerators R are withdrawn through the passages w lying below them and the elbow pieces z into the waste gas flue Q on the left half side, and from there to the chimney stack. The waste gases from the other pair of regenerators L are withdrawn through the hollow shafts p into the flues P and pass through the reversing valve at their end into the chimney stack. After a certain period of working, the reversal of flow is effected in the usual manner, so that, conversely, the left half of the heating walls is supplied with fresh gas for combustion and that on the right hand is traversed by the discharged products of combustion.

When the oven is heated with rich gas the action is as follows:—

The gas mains g are supplied in this case with rich gas. The pipes f are open to the cocks h, the pipes q are closed. The gas for combustion is led to the side of the oven which is to be heated through the distributing flues a and the nozzles b at the foot of each flue H. The action of the regenerators L for preheating the air for combustion is the same as described in connection with heating with poor gas. The regenerators R, which are used in heating with poor gas for preheating the gas, are, in the case of rich gas heating, utilized for preheating air for combustion. It is assumed, as in the previous example, that the half of the heating walls on the right hand side, corresponding to Fig. 1b, is heated by the gas and the left half of the heating walls is traversed by the discharged products of combustion. In this stage of working, the valves y on the right side of the oven (that is in Fig. 1b) in the elbow pieces z which lead to the waste gas flue Q are closed; on the other hand, the covers x are open to the atmosphere. On the opposite left side of the oven (Fig. 1a), conversely, the valves y in the elbow pieces z are open and the covers x closed.

While the rich gas serving as the heating medium flows from below upwards through the distributing passage a on the right hand side (Fig. 1b) and the nozzles b into the flues H on that side, fresh air is drawn through the open cover x on the right hand side into the elbow piece z and into each chamber of the regenerators R. The preheated air for combustion flows through the hollow shafts r into the sole flues c through the branch passages m into the ducts i of the partition walls s and through the lateral outlets e into the heating flues H. At the same time further air for combustion flows, as in the previous example, from the reversing valve (not shown) at the end of the battery into the flues P shown in Fig. 1b, thence through the hollow shafts p into the regenerator chambers L, through the upper shafts l into the sole flues d and through the branch passages n into the vertical ducts j of the partition walls t and the lateral outlets o at the different levels into the flues H. In working with rich gas heating, all the ducts i and j are exclusively traversed by air for combustion. The whole quantity of air is distributed at different levels into the flues H and causes the combustion of the rich gas, introduced at the foot of each flue through the nozzles b, in a corresponding number of stages. The burnt gases are led within the heating walls over the horizontal main collecting flue v into the flues H on the left side of the oven hand, flowing downward through

these, are withdrawn exactly as in the previous example through all the regenerators R and L of that side of the oven and over the flues P and Q into the chimney stack. Also in this 5 case the working is changed over from one to the other side of the oven in the usual manner of reversing.

The previously described supply of the combustion media, heating gas and air through the ducts 10 *i* and *j* and through the various lateral outlets *e* and *o* arranged at different levels of the ducts, requires, obviously, in order to obtain a uniform 15 heating at all levels by the combustion at the different stages, that the outlets *e* and *o* should be suitably dimensioned in order to secure that the 20 quantities of the combustion media introduced at the various levels should be correctly proportioned. When heating with poor gas, where both combustion media, the gas and air are introduced 25 at different levels into the heating flues, it is not absolutely necessary that both substances should be distributed in similar proportions to the different levels. It is sufficient if, for example, the air for combustion is distributed in the correct 30 proportion over the whole height, so long as the quantities of the other combustion medium, the gas, varying from the bottom upwards, are at least proportional to, or in excess of, the air, since, obviously, the quantity of the combustion material, of which there is the smallest amount available, that is, on the present assumption, the air, 35 determines the extent of the combustion in each individual step. The limit case of this kind where the proportions are differentiated as explained is effected by the rich gas heating, since then the whole of the heating gas enters directly the bottom of the flue and there is an excess of gas in proportion to the air at all levels except at the uppermost position of the air supply.

Owing to these conditions, the arrangement can 40 advantageously be such that the cross-sections of the outlets *e* for the one group of ducts *i* differ from those of the outlets *o* of the other group. In this way, it is clear that the quantities of air 45 for combustion which are introduced into the various levels, when heating with poor gas, in which case the air is only supplied through one group of ducts *j*, can be proportioned differently than when heating with rich gas, in which case 50 the air is supplied in common through both groups of ducts *i* and *j*. This difference in proportioning the air, respectively, in the two conditions of heating can be utilized, if, in dependence on the 55 properties of the two gases, different quantities of air are distributed for the production and transmission of the same quantity of heat. Also, by the change in the distribution of the proportions of the air, can allow to a certain extent, for example, for the different rates of combustion of 60 rich gas and poor gas. The invention provides, therefore, means for very considerably adapting and modulating the arrangements in ovens of the present type, so that a uniform heating at different levels is ensured, when the heating conditions are varied by employing gases of very 65 different properties.

The above-described construction of the sub-structure of the oven according to the invention, in which each half of the oven is provided with 70 two pairs of regenerator chambers connected in parallel, that is altogether four regenerators, with the intermediate supporting walls, has consider- 75 able advantages as regards the stability of the oven and the construction of the regenerator chambers themselves. The whole of the lower

part of the oven can be utilized for the arranging of the regenerators, while still allowing room for strong supporting walls of considerable thickness. At the same time the uniform grouping of the supporting walls over the length of the oven provides a very satisfactory and uniform support for the whole upper structure of the oven. This 10 is due to the fact that, if the supporting walls expand vertically when heated, there is a uniform effect in the vertical direction on the whole sole of the oven chamber, so that the chamber soles remain uniformly flat and horizontal. Also, by the arrangement according to the invention of four regenerators in each half of the oven, the 15 regenerator chambers have, such dimensions parallel to the length of the oven chambers, that the same are sufficiently wide for convenient passage and working of men during construction and also for fitting and completing the chequer-work, while, on the other hand, they are small enough 20 to ensure a suitable constructional design.

Only in this way would it be possible, for example, to obviate the provision of an arch at the upper portion of each chamber, and to enable it to be replaced by inclined extensions of 25 the supporting side walls. The omission of the arch is especially important because the roofs of regenerators must be pierced by the necessary 30 passages which considerably weaken the arched roofs. Four is the best number of regenerators 35 in each half of the substructure and affords the greatest advantage. If the number of the regenerator chambers were increased, the width both of the chambers and of the supporting partition walls, would be unavoidably diminished 40 and would unfavourably detract from the stability of the substructure of the oven. The arrangement in which the four regenerator chambers of each half of the substructure are combined into two pairs connected in parallel is particularly 45 convenient for regenerative ovens adapted for poor gas heating, since both these pairs of regenerators can be utilized for preheating two different mediums for combustion, namely, heating gas and air. The arrangement according to the invention of the regenerators is not restricted to the example shown in the drawings in which the heating walls are divided into 50 two halves operating alternately as the flow of the products is reversed. On account of the plurality of regenerators provided, the heating walls may be divided into more than two groups of flues and these can be connected with corresponding regenerators working alternately on reversal of the flow. Obviously, in this respect 55 the arrangement according to the invention gives considerable scope in the design.

What I claim is:

A coking chamber, a heating wall therefor, said heating wall comprising a row of vertical 60 combustion flues, a duct in each of the partitions between each two adjacent combustion flues, said duct connecting with each of said two combustion flues at a plurality of levels, a regenerator communicating with the ducts in 65 the alternate partitions in a part of said row, a separate regenerator communicating with the ducts in the intermediate partitions in said part of said row, a regenerator communicating with the ducts in the alternate partitions in the remainder of said row, and a separate regenerator 70 communicating with the intermediate ducts in said remainder of said row.
